UNITED STATES PATENT OFFICE.

CHARLES HOYLE, OF EL ORO, MEXICO, AND HARRY A. GUESS, OF FLAT RIVER,
MISSOURI.

CLASSIFIER.

1,007,205.

Specification of Letters Patent. Patented Oct. 31, 1911.

Application filed June 8, 1910. Serial No. 565,801.

To all whom it may concern:

Be it known that we, CHARLES HOYLE, a citizen of the United States, residing at El Oro, State of Mexico, Republic of Mexico, and HARRY A. GUESS, a citizen of the United States, residing at Flat River, in the State of Missouri, have invented certain new and useful Improvements in Classifiers, of which the following is a specification.

10 This invention relates to improvements in classifiers and separators adapted mechanically to separate articles of different materials and different specific gravity and particles of the same material which vary in
15 size.

One of the principal objects of the invention is to provide a classifier which shall produce an effective and complete separation of extremely fine particles of material commonly known as slimes from the coarser particles which are commonly known as sands or concentrates.

Another object of the invention is to provide means for slowly but continuously discharging the coarser or heavier material in such a manner that it may be thoroughly washed and the lighter and finer material completely separated therefrom.

The further objects of the invention will be hereinafter more fully set forth in the following description of one form of apparatus embodying the invention, which consists in the new and novel features of construction and combinations of parts set forth
35 and claimed.

In the accompanying drawings: Figure I represents a side elevation partly in section of the classifier. Fig. II represents a plan view of the same. Fig. III represents a detail view of one of the blades or scrapers.

The classifier comprises a settling box 1, which may be made of any suitable material, as wood, metal or fiber. The sides 2 are preferably vertical, but the ends are inclined, one of them, as 2^a, preferably having a steep pitch and the other, as 2^b, having a much more gradual pitch, and being extended a considerable distance above the level of the sides and the other end.

The material to be classified is fed to the settling box from any suitable source of supply through a trough 3. Said trough is

preferably provided with a plurality of openings 4 through its bottom, whereby the material is delivered to the settling box with 55 as little disturbance as possible. A baffle plate 5 may be arranged immediately below said trough so as to properly distribute the material over the bottom of the settling box.

An overflow pan 6 is arranged in the box 60 so that its top will be slightly below the top of the sides. The pan is centrally located in the box and is shallow near its edges, so that the bottom thereof will form a shelf or baffle, which will tend to break up any ascending 65 currents which might carry coarser material than is desired. The pan communicates through a suitable spout or opening 7 with an outlet pipe 8 which passes through the sides of the settling tank to convey the 70 slimes. The top of the pan is preferably provided with an adjustable bead 9 whereby the height thereof may be varied somewhat if desired.

In order to remove the coarse material 75 from the settling box, an endless carrier is provided, which comprises blades or scrapers 10 secured in any well known manner to sprocket chains 11. Said chains are driven by sprocket wheels 12 and 14 keyed to shafts 80 15 and 16 respectively, which are rotatable in suitable bearings provided on the settling box. The sprocket wheel is of sufficient diameter to extend above and hold the scrapers out of the liquid during the return 85 or non-operative part of their travel. Suitable means, of any well-known construction, as the train of gears 17 and 18 are provided whereby the scrapers may be driven at desired speeds. The sprocket wheels and chain 90 permit the scrapers to be employed with a minimum disturbance of the body of liquid.

An outlet 19 is provided near the upper end of the sloping extended bottom 2^b of the settling tank for the discharge of the 95 coarser material on to a conveyer of any suitable or desired construction. A pipe 20 provides means for delivering a quantity of water or other liquid such as a solution of cyanid or other chemicals against the 100 coarser material which is being dragged up the inclined bottom, thereby thoroughly washing same and removing all of the slimes or fine material.

In operation the material to be classified is delivered by a current of water or other liquid to the feed trough, from which it passes through the openings provided there-
5 in over the baffle plate into the settling box. The overflow pan is absolutely horizontal so that the water and slimes or finer material will flow over the edge in an even stream and be discharged through the dis-
10 charge pipe 8, while the coarse material settles to the bottom. The coarse material is then drawn by the scrapers 10 up the inclined bottom, which is of sufficient length to permit most of the water or other liquid
15 which is drawn out of the settling box or delivered from the supply pipe to drain off.

By this construction a very close division can be obtained between the material dis-
20 charged to the overflow pan and the ma-
terial removed by the scrapers. Heretofore much difficulty has been experienced in the separation of materials because a quantity of slime has almost invariably been removed with the coarse material and a certain
25 amount of fine sand has been removed with the slimes, thus interfering with the subse-
quent treatment of each product. The ar-
rangement of parts herein disclosed pro-
duces a clear line of demarcation, which can
30 be regulated to some extent by the adjust-
able bead 9 on the top of the overflow pan.
The discharge of the coarse sand is con-
tinuous and in one direction, over a distance sufficient to prevent waste of the liquid or
35 solution which is used.

Although one form of mechanism em-
bodying this invention has been shown and
described, it is obvious that various changes
within the skill of the mechanic may be
40 made in the details of this mechanism with-
out departing from the spirit of the inven-

tion, provided the means set forth in the following claims be employed.

We claim as our invention:

1. In a classifier the combination of a 45 settling box having an inclined bottom ex-
tending above the overflow level, an extend-
ed overflow pan in said box spaced from
the ends thereof and presenting an overflow
edge, a conveyer in said box encircling the 50
overflow pan in a vertical plane and com-
prising an endless series of transverse
spaced scrapers extending across said box
and adapted to engage the bottom, said se-
ries extending along said bottom to above 55
the liquid level.

2. In a classifier the combination of a set-
tling box having an inclined bottom extend-
ing above the overflow level, a horizontally
extended overflow pan having an approxi-
mately flat bottom adapted to serve as a 60
baffle retarding the direct upward flow of
liquid from the bottom of the box, said pan
being spaced from the ends of the box and
presenting an overflow edge, a conveyer in
65 said box encircling the overflow pan in a
vertical plane and comprising a series of
scrapers adapted to engage the bottom, said
series extending along said bottom to above
the liquid level.

This specification signed and witnessed
this 28 day of May and this second day of
May, A. D., 1910.
